UNITED STATES PATENT OFFICE.

PETER FREDRICK WALSTROM, OF BIRMINGHAM, ALABAMA.

MOLDING-MACHINE.

960,455.

Specification of Letters Patent.

Patented June 7, 1910.

Application filed August 31, 1909. Serial No. 515,534.

To all whom it may concern:

Be it known that I, PETER FREDRICK WALSTROM, a citizen of the United States, residing at Birmingham, in the county of Jefferson and State of Alabama, have invented certain new, and useful Improvements in Molding-Machines, of which the following is a specification, reference being had to the accompanying drawings.

10 My invention relates to improvements in machines for making sand molds for use in casting articles from metals.

The object of the invention is to provide a simple and practical machine of this character which will be entirely automatic in operation and which has improved means for supporting or locking the stripping plate while the pattern is being withdrawn.

With the above and other objects in view, 20 the invention consists of the novel construction, combination and arrangement of parts hereinafter fully described and claimed, and illustrated in the accompanying drawings in which—

25 Figure 1 is a view partly in elevation and partly in section of a molding machine embodying my invention. Figs. 2 and 3 are horizontal sectional views taken respectively on the planes indicated by the lines 2—2 and 3—3 in Fig. 1. Fig. 4 is a detail vertical section showing the cam latch for supporting and locking the stripping plate. Fig. 5 is a detail vertical section showing the stops for the pattern table. Fig. 6 is a 35 perspective view of the pattern table, and Fig. 7 is a perspective view of the upper portion of the frame or support.

Referring more particularly to the drawings 1 denotes a suitable base on which is 40 mounted a frame or support consisting of two side members 2 united by upright members 3, which latter form supporting standards and have their lower ends secured to the base. The upper portions of the end members or upright plates 3 are formed with inwardly extending flanges 4 as seen in Fig. 2, and these flanged upper portions have their inner faces grooved or recessed as shown at 5 to form guide ways for a 45 stripping plate 6.

50 7 denotes a flask arranged on the stripping plate and adapted to receive the sand into which a pattern or patterns 8 are forced through openings in the stripping plate. 55 While the patterns may be of any shape and size according to the article to be molded,

those illustrated are adapted to form molds for making the curved portions of brake-shoes and they are arranged on cross bars or pedestals 9 on the top of a pattern table 10. 60 The latter is at the top of the rod 11 of a piston 12 which works in a cylinder 13 on the base 1. Compressed air or other fluid under pressure is supplied to the bottom of the cylinder 13 by a pipe 14, the admission 65 and exhaust of compressed air being controlled by a suitable valve 15.

Upon the side edges of the pattern table 10 are projecting arms 16 in which are arranged set screws 17 at similar adjustable 70 stops adapted to engage the side members or plates 2 to limit the upward movement of the pattern table. Said pattern table is also provided upon its four corners with upright guide lugs 18 of angular shape in cross 75 section and arranged for sliding engagement with the flanged upper portions of the end members or uprights 3, as clearly shown in Figs. 3 and 4 of the drawing. The lugs 18 are also adapted to engage the stripping 80 plate 6 and lift it off of the shoulders 19 formed by the bottom portions of the guide grooves 5, as will be understood on reference to Fig. 4.

The usual relatively stationary platen 20 85 is provided, the same being adjustable by means of a screw 21 and removable by being disposed in the usual swinging frame 22.

Depending from the end portions of the stripping plate 6 are supporting and guiding 90 pins 23 which slide through guide lugs 24 on the inner faces of the end members or uprights 3. The lower ends of the pins 23 are adapted to be engaged and supported by latch levers 25 pivoted intermediate their 95 ends 26 on the inner faces of the members 3 and having a curved or cam shaped portion at one end and a counterbalancing weighted portion 27 at its other end. The cam shaped ends of the latch levers 25 are 100 provided with pins 28 to work in slotted portions 29 of links 30 pivoted at 31 to the end portions of the pattern table 10 and depending from the latter. Owing to this connection between the pattern table and the latch, 105 said table will have the limited movement independent of the latch for the purpose of allowing the patterns to be withdrawn before the latches release the stripping plate.

In operation, when the piston is in the 110 lower portion of the cylinder and the stripping plate is in lowered position or resting

on the shoulders 19, the patterns and flasks are placed in position, the flasks filled with sand and the stationary platen 20 is adjusted into position. The valve 15 is then manipulated to admit compressed air beneath the piston 12, whereupon the table 10 will move upwardly and the lugs 18 on its corners will pick up and elevate the stripping plate 6 and the parts thereon so that the sand in the flask will be compressed around the pattern. When the parts are in lowered position the pins 28 are in the upper ends of the slots 29 of the links 30 so that the latch levers or cams 25 will not be swung under the supporting and guiding pins 23 until the bottom portions of the slots 29 lift the pins 28 on said latch levers. When the valve 15 is again manipulated to permit the air beneath the piston to escape, the weight of the parts supported by the piston will cause them to descend so that the pattern table 10 will lower or withdraw the patterns 8. However, owing to the disposition of the latch levers or cams 25 beneath the pins 23 the stripping plate will be retained in its elevated position until the upper portions of the slots 29 engage the pins 28 and swing the latch levers or cams from beneath the pins 23, whereupon the stripping plate will drop on to the supporting shoulders 19.

Having thus described the invention what is claimed is:

1. In a molding machine, the combination of a stationary platen, a supporting frame, a stripping plate having limited movement in the latter, a pattern table having movement independent of the stripping plate and adapted to elevate the same, means for actuating said pattern table, supporting pins extending from the stripping plate, pivoted latch levers upon said frame and having counterbalanced cam portions adapted to engage and support said pins, and links upon the pattern table and having slot and pin connection with said latch levers.
2. In a molding machine, the combination of a stationary platen, a supporting frame, a stripping plate having limited movement in the latter, a pattern table having movement independent of the stripping plate and adapted to elevate the same, means for actuating said pattern table, adjustable stops carried by the table and adapted to engage

said frame to limit the upward movement of 55 the table, supporting pins extending from the stripping plate, pivoted latch levers upon said frame and having counterbalanced cam portions adapted to engage and support said pins, and links upon the pattern table and having slot and pin connection with said latch levers.

3. In a molding machine, the combination of a stationary platen, a supporting frame, a stripping plate having limited movement 65 in the latter, a pattern table having movement independent of the stripping plate and adapted to elevate the same, a fluid pressure cylinder and piston for actuating said pattern table, supporting pins depending from 70 the stripping plate, pivoted latch levers upon said frame and having counterbalanced cam portions adapted to engage and support said pins, and links upon the pattern table and having slot and pin connection 75 with said latch levers.

4. In a molding machine, the combination of a base, upright frame members rising therefrom and having at their upper ends inwardly projecting side flanges, the inner 80 faces of the upper ends of said members being formed with guide recesses, side members uniting the inwardly extending flanges of the upright members, a stripping plate slidably engaged with the guide recesses in 85 said upright members, a pattern table formed at its corners with upright angular guide lugs to slidably engage the inner faces of said upright members and to engage and elevate said stripping plate, said table being 90 formed on its sides with outwardly projecting lugs having vertical screw threaded openings disposed beneath said side members, stop screws in said openings of the lugs and adapted to engage the bottom 95 edges of said side members, means for actuating the pattern table, means for supporting the stripping plate in elevated position, a stationary platen, and means actuated by the movement of the pattern table for moving 100 said stripping plate-supporting means into and out of operative position.

In testimony whereof I hereunto affix my signature in the presence of two witnesses.

PETER FREDRICK WALSTROM.
